DESIGN FOR A PLATE OR SIMILAR ARTICLE

Anton Eckert, Alameda, Calif.

Application November 20, 1933. Serial No. 49,807

Term of patent 7 years

To all whom it may concern:

Be it known that I, ANTON ECKERT, a citizen of the United States of America, and a resident of the city of Alameda, county of Alameda, State of California, have invented a new, original, and ornamental Design for a Plate or Similar Article, of which the following is a specification, reference being had to the accompanying drawing, forming part thereof.

I claim:

The ornamental design for a plate or similar article substantially as shown and described.

ANTON ECKERT.
